MACHINE FOR PEELING OR CLEANING
VEGETABLES AND THE LIKEFrederick Hursh Wright and Edmund Woodward
Lewis, London, England, assignors to The Cen-
tury Machine Company, Cincinnati, OhioApplication April 26, 1932, Serial No. 607,588
In Great Britain May 22, 1931

5 Claims. (Cl. 146—49)

This invention relates to machines for peeling or cleaning vegetables or the like, and particularly relates to machines of the type having a container into which the vegetables or the like are inserted, and a rotary plate or disc mounted in the container, such plate or disc being lined with abrasive material, such as carborundum, which effects the peeling or cleaning.

In machines of this kind the rotating parts in the container are liable to become choked with peelings and foreign matter, and in order to facilitate effective cleaning of the container it is essential to provide for the removal of the rotary plate or disc, and for this purpose the rotary plate or disc usually engages the driving shaft by means of a square or key and is fixed in position by means of a nut, which latter to a non-mechanical user is a frequent source of trouble, and in consequence is sometimes not screwed on firmly or is omitted altogether when the plate or disc is replaced. Furthermore, machines of this kind are frequently overloaded by the insertion of more vegetables or the like at a time than the container is constructed to hold, and also by the vegetables or the like becoming jammed between the rotating parts and the container. When such overloading occurs the machine is stopped or the motor is very much overloaded with consequent damage thereto.

The present invention has among its objects to provide an improved means for fixing the rotary plate or disc upon the driving shaft and for preventing overloading and consequent damage to the electric driving motor.

According to the present invention the rotary plate or disc referred to is adapted to engage helically arranged splines on the shaft, which splines are arranged at such an angle in relation to the direction of rotation that when the machine is in operation the plate or disc tends to bind or lock itself upon the shaft, while when the machine is stopped the plate or disc may be readily removed by turning it in the direction of rotation.

According to a further feature of the invention a clutch device is incorporated in the drive between the motor and the rotary plate or disc, such clutch device being of that type which when the torque exceeds a pre-determined amount will allow slipping or relative rotation of the parts, and preferably being of the kind in which spring pressed balls mounted in one clutch member engage in recesses in the other clutch member, the engagement and disengagement of the balls when slipping occurs affording an audible indication of the overloading of the machine. The clutch

or automatic release device preferably is arranged in the end portions of the motor casing or otherwise so that one clutch member may be mounted directly upon the motor shaft.

The invention is illustrated in the accompanying drawing in which

Figure 1 is a part sectional elevation through a machine for peeling or cleaning vegetables or the like embodying the features of the present invention; and

Figure 2 is a sectional elevation showing a modified form of driving means.

In carrying the invention into effect according to the construction shown, the improved machine comprises a cylindrical container 10 which is closed at the bottom 11 and is mounted upon a hollow pedestal preferably made in upper and lower parts 12 and 13 respectively, the upper part 12 being adapted to form the gear box of the machine. At the top the container 10 is provided with a removable cover plate 14 having a feeding hopper 15 which may be provided with a suitable closure cap (not shown), a pipe fitting 16 being arranged for introducing a stream of water into the container 10. A vertical shaft 17 is mounted to project upwardly into the container 10, such shaft at its lower end being carried in a suitable bearing 18 in a transverse member 19 of the pedestal 12, 13, the upper end of the shaft 17 being arranged to extend through a boss 20 provided upon a transverse plate 21 forming the top of the pedestal upon which the container 10 is fixed.

The upper end of the shaft 17 passes through a boss 22 formed in the bottom 11 and its extremity 35 is shaped with helical splines 23 which engage with corresponding threads or grooves formed in a boss 24 carrying the rotary disc 25 which may conveniently be of saucer-like formation, the top of the bore in the boss 24 being closed by a 40 screwed plug 26. The splines 23 are so arranged that when the driving shaft 17 is rotated in the normal direction, the rotary plate or disc 25 tends to move downwards upon the shaft 17 and thus seats itself upon a shoulder or collar 27 on the 45 shaft 17, or other suitable abutment.

An annular depending flange 28 is arranged concentric with the boss 24 and carries a tubular sleeve 29 bearing one or more planes 30 which serve to expel dirt, peelings and other foreign 50 matter through a discharge outlet 31 formed in the container 10. In order to prevent other such foreign matter and water from entering the working parts of the machine, the boss 22 is provided with a screwed-cap 32 enclosing a pack- 55

ing washer 33 which bears upon the shaft 17. It will be observed that by this means it is necessary for water or other foreign matter to find its way in an upward direction between the sleeve 29 and the cap 32 before it can even gain access to the packing washer 33. A washer 34 of comparatively hard rubber or rubber-like material, forms an effective joint and is of such character as not to introduce any substantial friction. Any water leaking past the packing washer 33 will be prevented from reaching the gear box by a ring 33a rotating with the shaft, as such water will be thrown outwardly by centrifugal force.

Referring to Figure 1, an electric motor 37 is bolted to or incorporated in the part 12 of the pedestal and is arranged to drive a worm-wheel 38 through the medium of a worm 39 in direct communication with the motor 37. The worm-wheel 38, is rotatably mounted upon the shaft 17 but is provided upon its upper surface with projections 49 having sloping sides, which projections 40 interengage with similar lateral recesses in a driven disc 41, the latter being slidably mounted upon the shaft 17 but in driving connection therewith by means of one or more splines or keyways 42. The disc 41 is normally held in engagement with the worm-wheel 38 by means of a coiled compression spring 43 which acts between a flange 44 on the shaft 17 and an adjusting nut 45 upon a screw threaded collar 46 formed as one with the disc 41. By this means the normal driving torque may be readily transmitted from the worm-wheel 38 to the disc 41 so driving the disc or plate 25, but should the latter become jammed or should an overload otherwise occur, projections 40 pass out of the corresponding recesses in the disc 41, thus preventing damage to the motor 37 and providing an audible warning.

A modified form of driving clutch is shown in Figure 2 in which the clutch casing 48 is incorporated in the end of the motor 37, the driving shaft 49 of which is provided with a driving disc 50 formed with holes accommodating spring-pressed balls 51 and provided with a flange ring 52 by which a driven disc or member 53 is retained normally in contact with the disc 50. The balls 51 normally engage recesses formed in the disc 53 but upon an overload occurring, the excessive torque overcomes the spring pressure of the balls 50 and the driving connection between the discs 50 and 53 is broken, again providing an audible warning. The driven shaft 54 passes into the pedestal 12 and is provided with a driving worm 39 as before. Lubrication conveniently is effected by forcing oil up through a central passage 55 in the vertical shaft 17 and through a radial passage 56 to the upper bearing from which the oil drips on to the worm-wheel 38 and is thrown thereby on to the bearings (not shown) of the shaft 54, any excess oil draining into the base of the pedestal portion 12 through a passage 57 whence it passes to a suitable pump propeller or plunger operated from the lower end of the shaft 17. This pump (not shown) is preferably of the type having an eccentric rotor and diametrically arranged spring, the rotor being mounted at the lower end of the vertical shaft and being adapted to be directed therefrom.

In the operation of the machine, vegetables and the like are inserted through the hopper 15 and the plate or disc 25 is revolved, thus causing the vegetables to rub against the abrasive surface of a liner 58 of the container 10, while the peelings, dirt and other foreign matter are washed out through the aperture 31 by water injected through

the fitting 16. After treatment, the vegetables or equivalent are removed through an aperture 59 which is normally closed by means of a door 60 having a lining 61, said door 60 being operated by means of a handle 62 working in conjunction with a link 63.

What we claim is:—

1. In a machine of the character described, a container having a fixed bottom, a driven shaft projecting upwardly through the bottom of the container, and a plate carried by the upper end of and rotatable with the shaft within the container and constituting a rotatable bottom member therefor, the upper end of the shaft having a screw threaded portion within the container with its threads extending in a direction reverse to that of the rotation of the shaft, the plate having a central opening with the wall of the opening screw threaded and screwed upon the threaded portion of the shaft and constituting the sole connection between the plate and the shaft, and driving means for the shaft including an overload clutch.

2. In a machine of the character described, a container having a fixed bottom, a driving shaft projecting upwardly through the fixed bottom and into the container and provided with a screw threaded top portion within the container with its threads extending in a direction reverse to that of the rotation of the shaft, and a plate carried by and rotatable with the shaft within the container and constituting a rotatable bottom member therefor, said plate having an opening extending therethrough, one end portion of the opening having its walls provided with coarse screw threads screwed upon the threaded portion of the shaft and constituting the sole connection between the plate and the shaft, the opposite end portion of said opening being provided with finer screw threads, and a closure plug engaging the finer threads of the opening in the plate.

3. In a machine of the character described, a container having a fixed bottom provided with a central elevated portion having a shaft opening 45 therethrough and a stuffing box for said opening, the container having a discharge opening below the elevated bottom portion, a shaft extending through the bottom opening and the stuffing box and projecting into the container, a rotatable bottom member carried by the inner end of the shaft and rotatable therewith, a protecting sleeve depending from the rotatable bottom member and surrounding the stuffing box in close relation thereto, and expeller vanes carried by the protecting sleeve and extending radially outward therefrom and working in the space between the fixed and rotatable bottom members.

4. In a machine of the character described, a hollow pedestal having a gear box closed at its upper end and provided with a central shaft opening having an upstanding boss surrounding the opening, a container supported upon the top of the gear box and provided with a central elevated bottom portion having a shaft opening and a stuffing box therefor in alignment with the shaft opening in the top of the gear box, a shaft extending through the opening in the top of the gear box and through the stuffing box and into the container, a rotatable bottom member carried by and rotatable with the top portion of the shaft, a protecting sleeve depending from the rotatable bottom member, and a ring member carried by the shaft portion between the top of the gear box and the elevated portion of the bottom of the

container and embracing the boss on the top of the gear box.

5. In a machine of the character described, a hollow pedestal having a gear box, a shaft rotatably mounted in the bottom and the top of the gear box and extending upwardly therefrom, an overload clutch for the shaft located in the gear box, means for rotating the clutch, a container supported upon the top of the gear box and provided with a central elevated portion having a shaft opening through which the shaft projects,

a rotatable bottom member carried by the top of the shaft, a stuffing box provided upon the top of the elevated bottom portion, a protecting sleeve depending from the rotatable bottom member and surrounding the stuffing box in close relation thereto, the top of the gear box having a boss surrounding the shaft, and a water shedding ring carried by the shaft and embracing the boss. 5
